UNITED STATES PATENT OFFICE.

INNES T. VERDIN, OF GLENDALE, OHIO.

DELIVERY-GOODS RECEIVER.

1,028,918.

Specification of Letters Patent. Patented June 11, 1912.

Application filed January 18, 1912. Serial No. 671,002.

To all whom it may concern:

Be it known that I, INNES T. VERDIN, a citizen of the United States, and a resident of Glendale, Hamilton county, State of Ohio, have invented certain new and useful Improvements in Delivery - Goods Receivers; and I do declare the following to be a clear, full, and exact description of the invention, attention being called to the drawing which 10 accompanies this application and forms a part thereof.

This invention relates to devices adapted to receive temporarily merchandise, commodities, goods, etc., which are delivered 15 during the absence of the person for whom they are intended, the object of these devices being to protect such goods against theft and loss until taken in charge by the proper person.

20 The device of the invention is constructed more particularly for use in connection with the delivery of milk which is often brought to houses at times when none of the inmates are about. Such a temporary receiver being provided, the goods may be left nevertheless, because the closing of said receiver, after the goods are deposited therein, causes it also to become automatically locked, so that thereafter, it cannot be opened, except 25 by one who is provided with a key.

The invention consists of the construction as hereinafter described and claimed and as shown in the accompanying drawing, in which:

35 Figure 1, is a vertical cross-section of the device taken on line 1—1 of Fig. 3, and as it appears in inoperative condition and partly open. Fig. 2, in a similar view shows the device closed and in locked condition. Fig. 40 3, is a top view of the device with the top removed and as it appears before being closed. Fig. 4, shows in perspective view, somewhat enlarged, the operating and locking mechanism.

45 As before stated, the device is constructed with a special view for use in connection with the sale of milk when delivered in bottles and as to size it may be arranged to receive one or more of them. As shown, the 50 device has a capacity for receiving two bottles. These latter come usually in pints and quarts, each of standard size and the device is designed to be adapted for receiving bottles of either size. The necks 6 of these 55 bottles are substantially of the same diameter,

irrespective of their size otherwise, and terminate in an enlarged rim 7 around their mouths.

The device consists substantially of a box 60 constructed of suitable material and adapted for attachment in a position conveniently accessible. It is provided with a door 8, hingedly connected to the body to swing on a vertical axis. Near the free edge of this door a latch 9 is pivotally attached so as to project inwardly, the possible movement of the latch being in a vertical plane, but limited, so that said latch may not drop lower than shown in Fig. 1. A notch 10 is provided in the lower edge of this latch and beyond this notch the edge is inclined as 65 shown at 11. When the door is closed this latch is adapted to co-act with a complementary keeper 12, provided the same is in proper position for the purpose. This 70 keeper is pivoted inside of the box, its free end forming a check 13 adapted to be received by notch 10. Under normal, that is 75 inoperative conditions, and as shown in Fig. 1, the door may be readily opened and if 80 closed, no engagement will take place between latch and keeper, because this latter occupies a position out of reach of said latch and below the same. Observe also dotted 85 lines in Fig. 2. The act of placing a bottle inside of the box, raises the keeper to a position as shown in Fig. 2, so that when the 90 door is now closed, the inclined end 11 of the latch will contact with check 13 and slide up on the same. When notch 10 has arrived above the check, the raised latch drops again and becomes engaged to the keeper. This adjustment of the keeper is accomplished by means of an arm 14 rigidly attached to a rocker-rod 15 which is supported in suitable bearings inside of the 95 box. The end of this arm is curved as shown, and adapted to be engaged by the closed bottle-top in a manner to be lifted thereby when the bottle is being placed in 100 position. 16 is another arm also rigidly connected to rod 15 and positioned to be above the keeper to which it is connected by a link 17.

It will now be seen that when arm 14 is 105 acted upon by the placing of a bottle, arm 16 will also be affected by reason of the connection of both to rocker-rod 15. Keeper 12 will be raised in consequence and brings check 13 in the way of latch 9, in which 110

position it is now held, so that when the door is now closed, latch and keeper become engaged, thereby locking the door.

To assure proper co-action between the closed top of a bottle and arm 14, the bottle must be placed in a certain particular position and to obtain this result brackets are provided on which these bottles must be suspended, the bottom of the box being inclined as shown at 18 to prevent any other position. Each bracket is formed of a pair of spring arms 19, rigidly connected inside of the box and curved to fit partly around the neck of a bottle below rim 7 thereof. They are spaced so that some force is required to push a bottle in place, after which the arms close up tight against the neck thereof and gripping the same hold the bottles in position. There is a bracket for each bottle, according to the intended capacity of the box and a latch-setting arm 14 above each bracket, so that the placing of one bottle upon any bracket is sufficient to raise the latch into operative position. By preference I provide pusher arms 20 on the door, opposite the open part of the brackets, said arms being adapted to act upon a bottle in case the same has not been carefully placed, for the purpose of forcing the same to its proper position necessary to act upon arm 14.

It will now be understood, that if the person who delivers the goods closes door 8, after having placed said goods in the intended manner, the door becomes also locked and access can be had thereafter only by disengaging latch 9, from the check of keeper 12. A key 21 is provided for this purpose to be used by the person authorized to have access. Removal of the bottles restores the mechanism again to its inoperative position shown in Fig. 1, whereby the receiver is rendered accessible for another deposit of goods. To prevent the door from flopping about its hinges, or from remaining partly open, a spring 22 is provided which holds the door against the box.

As will be seen, the placing of the goods is restricted to a fixed position which insures proper operation of the mechanism. Deposit in any other position is prevented in the manner shown and described and top 23 is also made convex, to prevent placing of any goods on it.

In the present case, the device being constructed for receiving bottled milk, arrangement is made whereby the larger and heavier bottles are partially supported to relieve bracket-arms 19 of excessive weight.

This is done by a ledge 24, which provides a partial support for the larger sized bottles, so limited however that the bracket arms must nevertheless be used to hold them in position, thus insuring the intended actuation of the mechanism. 60

Having described my invention, I claim as new:

1. In a device for the temporary reception of delivery goods, the combination of a box, a door for the same, key-operatable locking mechanism to hold the door in closed position, but normally in inoperative condition, a bracket consisting of spaced complementary gripping arms, rigidly secured inside of the box and opposite the door, they being of elastic material to impart spring action, and adapted to support a bottle placed between them by engaging the same at the neck thereof, a pusher on the door opposite the bracket and adapted to act upon the bottle for the purpose of insuring proper placing of the same upon the bracket, means provided above the bracket and susceptible of being actuated by a bottle while being placed between the gripping arms of the bracket, and intermediate devices whereby these means are operatively connected to the locking mechanism and whereby this latter is caused to become operative when a bottle is placed within the box. 80

2. In a device for the temporary reception of delivery goods, the combination of a box, a door for the same, a key-operatable latch pivotally secured to the inner side of the door, a keeper adjustably supported inside of the box and adapted to co-act with the latch for holding the door in closed position, but normally inoperative, a bracket provided inside of the box opposite the door thereof and permitting suspension of a bottle in the manner stated, a rocker-rod mounted in the box above this bracket, an arm on this rod, a link whereby it is connected to the keeper and an additional arm on this rod and positioned to be above the bracket mentioned and in a position so as to be actuated by the top of a bottle while the same is being placed upon the bracket, whereby the keeper is caused to assume a 110 position in which it becomes capable of co-acting with the latch. 100

In testimony whereof, I hereunto affix my signature in the presence of two witnesses.

INNES T. VERDIN.
